UNITED STATES PATENT OFFICE.

ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

ELECTRIC-BRAKE CONTROLLER.

Application filed November 20, 1918. Serial No. 263,309.

To all whom it may concern:

Be it known that I, ERNEST B. THURSTON, a citizen of the United States of America, residing at Toledo, Lucas County, Ohio, have invented new and useful Electric-Brake Controllers, of which the following is a specification.

This invention relates to electric controlling mechanisms, especially for alternating 10 current circuits.

This invention has utility in connection with gradual current flow change, particularly in association with a switch, as in elevators.

15 Referring to the drawings:

Fig. 1 is a wiring diagram of an embodiment of the invention as a slow up-stop apparatus for rendering more easy and accurate bringing of high speed alternating 20 current driven elevators under differing loads to proper landing positions;

Fig. 2 is an enlarged detail of the controller; and

Fig. 3 is a wiring diagram, similar to Fig. 25 1, with supplemental retarding features in the controlling mechanism, as well as polyphase adaptation thereof.

The alternating electric current motor 1 is mounted on drive shaft 2 carrying brake 30 drum 3 embraced by a pair of opposing brake shoes 4 normally thrust into holding position by a spring 5 to hold the member 3 as a brake from rotation when the motor 1 is cut off from driving. The shaft 2 carries 35 a worm 6 in mesh with worm wheel 7 on shaft 8 carrying drum 9 about which passes hoisting cable 10 extending down the elevator shaft to car 11, movable to various landings 12. The cable 10 in its opposite direction from the drum 9, passes about guide pulley 13 to counterweight 14.

In the car 11 is a controller or handle 15 for manual operation in effecting car travels and stops. This controller 15 is pivotally 45 mounted on the bearing 16 and carries a contact 17, which in normal upright or central position for the handle 15, bridges between terminals 18, 19 connected by line 20.

Upon shifting the handle 15 to the right, 50 the contact 17 moves away from the terminal 18, but so travels as to close circuit between terminals 19, 21. In the electric cable to the car 11 is line 22 from the terminal 19, extending past emergency or terminal safety

switch 23 to supply line 24. From the terminal 21 in the same flexible cable to the car 11, extends line 25, past safety switch 26 to coil 27, and thence to terminal 28 to which supply line 29 extends. The coil 27 thus energizes the main switch for lifting contacts 30, 31. The contact 30 is thus moved to close circuit between terminals 32, 33, so that supply line 34 is connected to power line 35 to the motor 1. Simultaneously the contact 31 moves against terminals 28, 36, to 65 close circuit therebetween.

As the handle 15 is shifted still further to the right, the contact 17, still against terminals 19, 21, also comes to terminal 37, connected by line 38, past safety switch 39, 70 to direction switch coil 40 connected by line 41 to the terminal 28 for current flow with supply line 29. Considering the coil 41 as for the up direction switch, as thus energized, it lifts contacts 42, 43. The contact 42 75 moves against terminals 44, 45, and power current supply from the line 29, to the terminal 28, past contact 31, to the terminal 36, may be had by line 46 to the terminal 45, and thence by the contact 42, to the terminal 80 44, for line 47 to terminal 48 and by way of line 49 to the motor 1. Simultaneously the third line to the motor 1 is closed for current flow from the line 24 by line 50 to terminal 51 abutted by contact 43 also against 85 terminal 52, from which extends power line 53 to the motor 1. The motor 1 is accordingly given a threephase power current supply for rotating the shaft or member 2.

With this polyphase current supply to the 90 motor 1, there is release of the member 2 from its brake holding means. The current from the supply line 29 by way of conductors 28, 31, 36, 46, 45, 42, to the terminal 44, may be connected by line 54 to running brake 95 switch coil 55, from which extends line 56 to terminal 57, line 58, by way of conductors 52, 43, 51, 50, to complete circuit from the supply line 24 in energizing the running brake switch coil 55 for lifting contacts 59, 100 60. From the supply line 34, by way of conductors 33, 30, 32, a line 61 extends to terminal 62 against which the contact 59 is thrown for completing the circuit through terminal 63, line 64 to coil 65 at brake magnet 66, and thence by line 67 to terminal 68 abutted by contact 60, also engaging terminal 69 connected by line 70 to the terminal

51, having the line 50 connect it with the supply line 24. The third path of the circuit for the brake magnet 66, is from the power line 29, by way of terminal 28, contact 31, 5 terminal 36, line 71, to brake coil 72 connected to the line 67. The brake magnet 66 is thus energized for drawing together at the top against the throw out action of the spring 5, and so the brake shoes 4 are released from the brake drum 3 as the motor 1 is started to move the elevator 11 upward.

As the elevator car 11 in its travel approaches a floor or landing 12, the arm 15 may be moved centerward, or to have its 15 contact 17 get away from the terminal 37, the coil 40 is de-energized, and the motor 1 discontinues its driving action. The running brake switch coil 55 is also de-energized, changing the stronger polyphase 20 holding of the brake during running of the elevator as actuated by the motor 1, to single phase by conductors 29, 28, 31, 36, 71, 72, 65, 64, and from the terminal 63 by line 73 to reactance coil 74 of car carried magnet 25 75 having its magnetic circuit resistance varied by the shiftable means 76 changing the air gap therein, said means being shown as directly connected to the handle 15 for movement therewith. From the coil 74 extends line 77 to the terminal 62, and by conductors 61, 32, 30, 33, to supply line 34, for the main line switch coil 27 is still energized. It is to be noted the running brake switch coil 55, when energized, has the contact 59 short out the coil 74.

When the handle 15 has shifted the contact 17 just clear of the terminal 37, it is still at quite an angle from its central position, and the laminated shiftable means 40 of the magnet 75 is so disposed as to have a considerable air gap in the magnetic circuit of this second or car carried magnet. The single phase current through the coil 74 is thus considerable and as it is in series with 45 the brake magnet coils 65, 72, the ampere turns are effective for opposing the spring 5, which opposition of course may not be as great as the polyphase holding during car travel. The action of the coil 74 tends to 50 shorten the air gap by drawing the means 76 into minimum gap position, and there is thus provided an electromagnetic automatic handle or controller centering device. The tendency is thus for the released handle to 55 swing to car stopping position. But still greater utility is inherent in this controller mechanism, for the rate of travel toward the inactive central position may be slowed up or hastened by the operator, and thereby 60 the current consumption of the coil 74 reduced. This reduction of the current flow in the coil 74, likewise reduces the ampere turns holding action of the coils 65, 72, not by a step by step action, but gradually, so 65 as the magnet 66 weakens there is in like

rate a holding of the shoes 4 by the spring 5 against the drum 3 to preclude overhauling of the motor by the traveling car. In practice this means, the operator may have a high speed traveling alternating current 70 driven elevator with heavy or light load, and upon shutting off of the actuating motor, the handle 15 may be so shifted as to gradually apply the shoes 4, and thus without any jerking or concussion bring the car 75 smoothly and easily to an accurate landing position. When the contact 17 is moved centerward away from the terminal 21, the main switch coil 27 is de-energized and current flow is thus entirely cut off from the 80 coils 74, and 65, 72.

For effecting downward travel of the car 11, opposite shifting of the controller handle 15 is had. As the contact 17 moves away from the terminal 19, current flow for 85 energizing the main switch coil 27 is supplied, by the contact 17 now extending to terminal 78, connected by line 79 to the terminal 19. The further shifting of the controller handle 15 for reversing two of the 90 power lines to the motor 1, and thus changing its direction of driving rotation, brings the contact 17 to terminal 80, having line 81 extending past safety switch 82 to downward travel direction switch coil 83. The 95 energized coil 83, has its circuit completed by line 84, and by way of conductors 41, 28, to the supply line 29.

The coil 83 lifts contacts 85, 86. The contact 85 effects closing of power circuit from 100 the line 24, by conductors 50, 51, and a line 87 to the terminal 88, and from thence by the terminal 48 and the line 49 to the motor 1. The contact 86 effects closing of power circuit from the line 29 by conductors 28, 105 31, 36, 46, 45, and a line 89 to terminal 90, and from thence by the terminal 57, line 58, terminal 52, and the line 53 to the motor 1. Simultaneously with the supply of power current to the motor 1, the electromagnetic 110 brake is released, as described in connection with the up-travel of the car 11. In the shutting off of driving power for stopping the descending car 11, the movement of the handle 15 away from the terminal 81, establishes the same conditions for single phase 115 brake holding, with manually controllable dwindling current to full shut-off of the switch, as is possible in the ascending car, for the terminals 78 and 21 are connected. 120

There may be an interlocking control in the apparatus for lagging or retarding the full action of the running brake switch so the car 11 may travel without brake interference for a distance, should such be desired, as shown in Fig. 3. Here the shifting of the controller contact 17 to the terminal 21 connects up the line 25 past switch 26, to terminal 91, connected by line 92 to terminal 93, which latter is connected by line 130

94 to terminal 95. There is thus far no energizing of any coil, and accordingly no throw of any remote controlled switch. The further shifting of the controller contact 17 to the terminal 37, connects up the line 38, past the switch 39, to the up-direction coil 40. This lifting of the contacts 42, 43, also lifts contact 96, for shorting between the terminal 93 and terminal 97 for current flow by way of line 98, terminal 99, and line 100 to energize the coil 27, and thereby giving a retarding closing of the main line switch as to the direction switch. Besides completion of the power brake circuits for upward travel of the car 11, there occurs from the lifting of the switch by the coil 27, a movement of contact 101 for shorting between the terminals 91, 99. This insures a holding of the main line switch in after the controller contact 17 has left the terminal 37 for shutting off driving actuation of the motor 1. The retarded throwing in of the main line switch by the coil 27 on starting, precludes other than quick release of the shoes 4 from the drum 3, as the motor 1 takes hold for driving operation.

Accordingly for stopping the upward travel of the car 11, the movement of the controller contact 17 off the terminal 37 cuts out the motor from driving, but does not directly apply the brake thereto. The momentum of the traveling parts may thus be spent in slowing up the car, and the duration of the slowing up may be limited manually by completing the throw of the controller 17 to clear the contact 21. In practice hereunder this handling of converting the brake from polyphase to single phase and then further reducing the holding action by gradually weakening the single phase holding, has been worked out with no chatter trouble. The downward travel is analogous to that for lifting, but in energizing the coil 83 by circuit from controller terminal 80, down switch coil 83, lifts with the contacts 85, 86, a contact 102, shorting between the terminal 95 and terminal 103, connected by line 104 to the terminal 97, for circuit completion to the main switch 50 coil 27 as in the up travel.

While this diagram as described in its application to Fig. 3 may be complete and fully operative, additional wiring is shown therein for operating the brake magnet as polyphase during its dwindling before being switched off, and this is accomplished by the provision of an additional coil 105 adjacent the coil 74, coacting therewith as the coils 65, 72 coat at the brake magnet, for with the two coils at the brake there is more uniform pull, and likewise the pull at the controller is more uniform with the two coils than with the one. Lines 106, 107, from the coil 105 extend respectively to the terminals 68, 69, to have the circuit from supply

line 24 therethrough shorted for cutting out the coil 105 when the running brake switch coil 55 is energized, by the contact 60 acting between these terminals 68, 69, in a manner analogous to the action of the contact 59 as to the coil 74. Accordingly in the installation having coils 105 and 74 for the reactance or air-gap varying means 76, there is no pulling off of the brake magnet coils 65, 72, from polyphase to single phase, but the weakening is gradual. There is more current through the coils 105, 74, as the controller contact 17 leaves the terminal 80 or the terminal 37 in its movement toward switch cutting out or central position, and this current is uniformly reduced until only acting as single phase, with no abrupt change. The electromagnetic holding of the shoes 4 off the drum 3, thus allows the springs to gradually come into full braking position after the motor 1 discontinues driving action. There is further no trouble from possible brake chattering due to this polyphase action throughout.

With a minimum of mechanical complication, there is provided herein by simple electric controlling mechanism the maximum range of slowing up or flexibility in power control from a maximum to full cutting off. This opens up the fields of high linear travel rate and first class passenger travel installations of elevators to alternating current electric operation with quiet operation at all times for quick accurate stopping without bumping or jerking in responding to the most exacting requirements.

What is claimed and it is desired to secure by Letters Patent is:

1. An elevator, a brake therefor, means normally setting the brake into elevator holding position, a coil for releasing the brake against the action of the brake holding means, a motor for the elevator, a controller for the motor, a coil at the controller in series with the brake coil, and means shiftable with the controller in movement toward off position to act upon the controller coil for decreasing current flow therethrough thereby to reduce the holding action of the brake coil.

2. A brake, means normally setting the brake, a coil for releasing the brake against the action of the brake setting means, a controller for deenergizing the brake coil, and means shiftable with the controller in its deenergizing direction travel reducing the current in the brake coil before cutting out said coil.

3. A brake, means normally setting the brake, a coil for releasing the brake against the action of the brake setting means, a controller for deenergizing the brake coil, a brake switch operable for energizing the coil and affected by the controller for deenergizing the brake coil, and means shiftable with the controller in its deenergizing direction

- travel reducing the current in the brake coil before cutting out said coil.
4. Gradual setting means for an electromagnetic brake for an elevator embodying a coil for energizing the brake into releasing position for the brake, and an elevator controller having an armature and a coil in neutral position in maximum resistance position as to the controller coil, said controller coil being in series with the brake coil.
5. An elevator, an electric motor drive therefor, a normally set brake, a coil for releasing the brake, a switch for cutting in the

brake coil, a controller for the brake coil, switch, and motor, a controller coil in series with the brake coil, and means at the controller co-acting with the controller coil as the controller opens the brake coil switch to operate said controller coil in series with the brake coil as an increasing resistance for gradually reducing the holding action of the brake coil in slowing up the application of the brake.

In witness whereof I affix my signature,

ERNEST B. THURSTON.
